DRIVE TOOL

George J. Zetzer and Clarence L. Dracka, both of Port Clinton, Ohio, assignors to Port Clinton Manufacturing Company, Port Clinton, Ohio, a corporation of Ohio
Filed Sept. 13, 1961, Ser. No. 137,894
13 Claims. (Cl. 1-47)

This invention relates to drive tools and more particularly to drive tools adapted for drilling openings in concrete or masonry construction by impact and for driving or setting expansion anchor members in the drilled openings.

The invention embraces the provision of a drive tool having a handle portion and a slidable drive plunger embodying a fitting which is adaptable for accommodating expandable anchor members or studs wherein the anchor members are utilized to form openings in concrete or masonry to receive the anchor members, the fitting being reversible to accommodate both male and female anchor members.

An object of the invention resides in a drive tool having a handle portion of nonmetallic material, a driving plunger functioning in conjunction with a reversible fitting for retaining expandable anchor members in position to be driven by the tool.

Another object of the invention is the provision of a drive tool adapted for many purposes and particularly adapted for driving both male and female expandable anchor members into concrete and the like, the drive tool construction embodying a reversible fitting adapted to accommodate both male and female anchor members, the fitting being held to a handle structure by means of a resiliently biased clutch or locking means which automatically biases the fitting into engagement with a handle component.

Another object of the invention resides in a drive tool embodying a reversible fitting wherein one position of the fitting accommodates a female anchor member to be driven into concrete or the like and in another position accommodates a male anchor member, the change in the position of the fitting being effected by manipulation of a fitting retaining means without the use of tools.

Another object of the invention resides in a spring biased locking means embodying a detent and a cam arrangement for removably securing an anchor member guide fitting to a handle component, the locking means being of a construction to automatically engage a ledge on the guide fitting with the handle component to eliminate lost motion between the fitting and handle component during anchor member driving operations.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

FIGURE 15 is an end view of a female anchor member;

FIGURE 16 is an isometric view illustrating a form of wedge or spreading means for a female anchor member;

FIGURE 17 is a sectional view similar to FIGURE 14 illustrating the position of the female anchor member in forming a bore in the body of concrete;

FIGURE 18 is a view illustrating the method of shearing a portion of the female anchor member from the anchored portion, and

FIGURE 19 is a detail view illustrating the method of removing a sheared portion of the female anchor member from the guide member.

The drive tool of the present invention is especially adapted for sinking expandable anchor members into floors or walls of concrete or masonry but the tool may be used for driving other components into concrete or masonry.

Referring to the drawings in detail, the drive tool of the invention is inclusive of the tubular or sleeve-like body or body member 10 which is encased in or surrounded by a sleeve or holder 11 of semi-hard rubber or the like which may be bonded, vulcanized or otherwise secured to the exterior surface of the sleeve-like member or body 10. The holder 11 is formed with peripheral recesses 12 to assist the operator in firmly gripping the holder. The holder is provided at its upper end with an outwardly extending flange 15 to provide a measure of protection for the hand of the operator.

The tool embodies a removable guide member 34 which is reversible for use in guiding both male and female anchor members and a plunger construction 14 adapted to drive male anchor members into concrete or masonry construction. The plunger 14 includes a portion 16 which is snugly, yet slidably fitted within the interior of the body or sleeve member 10. The plunger is provided with a knurled head or anvil portion 17 which is adapted to be struck by a hammer or impact member 18 shown in broken lines.

The head 17 is brazed or otherwise fixedly joined to the end region of the plunger section 16. The plunger construction 14 is bored to snugly receive a plunger section 20 of lesser diameter than the plunger section 16.

The end region of the plunger portion 20 is preferably knurled or serrated as shown at 22 in FIGURES 8, 14 and 17 to fixedly retain the plunger portion 20 in the plunger portion 16. The plunger portion 16 is provided with a peripheral groove 24 accommodating a rubber O-ring 25 of conventional construction which engages the interior surfaces of the sleeve or body 10 providing a degree of friction to resist impact reaction which may otherwise

wise cause the plunger to be projected out of the body member 10.

The end 26 of the plunger portion 20 is adapted to engage the end of a male anchor member for driving the same and the end region of the plunger portion 20 provides a guide which is inserted in the interior of a female anchor member during the driving of such member. Removably assembled or carried by the sleeve or body member 10 is a removable guide member 28 which is reversible. The guide member in one position in the body member 10 serves to guide a male anchor member and, when disposed in a reversed position, another portion of the member 28 serves as a driving means for a female anchor member.

The guide member 28 is fashioned with a knurled flange portion 30 of enlarged diameter, one portion or tenon 32 extending axially from one side of the knurled portion 30 and a second portion or tenon 34 projecting axially from the opposite side of the knurled flange portion 30, as particularly shown in FIGURES 2 and 8. As previously mentioned, the guide member 28 is adapted for ready reversible assembly in the body or sleeve 10 and embodies means for urging or biasing the flange 30 into engagement with the body or sleeve member 10.

With particular reference to FIGURES 1, 2 and 4 through 7, the portion of the sleeve or body 10, projecting beyond the extremity of the rubber holder 11, supports an annular member or collar 40 having its exterior periphery knurled as shown in FIGURE 1. The collar 40 is rotatable on the supporting portion of the body 10. Formed in the wall portion of member 10 are transverse bores 42 and disposed in each bore is a ball or detent 44.

As particularly shown in FIGURES 5 and 6, each opening 42, adjacent the inner surface of the sleeve or body 10, is formed with a restricted throat 46 to limit the inward movement of the detents or balls 44. Formed in the peripheries of the tenon portions 32 and 34 of the guide member 28 and spaced equal distances from the flange portion 30 are grooves or recesses 48 and 50. As particularly shown in FIGURES 1, 2 and 4, each of the recesses 48 and 50 is formed by two convergently arranged frusto-conically shaped surfaces 52 joined by a cylindrical surface 54 forming the bottom of each groove.

As particularly shown in FIGURES 2 and 4, the position of the openings or bores 42 in the body member 10 with respect to the flange 30 is such that when the end of the body member 10 is in engagement with the flange, as shown in FIGURES 2 and 4, the detents or balls 44 may move inwardly in contact with one of the frusto-conically shaped surfaces 52 so as to bias the flange 30 into direct contact or abutting engagement with the end of the body member 10.

Resilient means is provided for biasing the balls or detents 44 into locking position. As particularly shown in FIGURES 5 and 6, the interior region of the collar or annulus 40 is formed with recesses 56, each recess having a cam surface 58 which is curved in a direction to converge toward the exterior cylindrical surface of the body 10, the collar 40 being rotatable relative to the body 10. The annulus or collar 40 is also formed interiorly with a circumferential recess 62 adapted to accommodate a coil spring 64.

Struck inwardly from a wall region of the collar 40 adjacent the circumferential recess 62 is a projection 66, shown in FIGURES 5 and 6, which forms an abutment for one end of the coil spring 64. As shown in FIGURES 4 and 6, the body member 10 is provided with an opening in which is press fitted a pin 68 which forms an abutment for the opposite end of the spring 64. The collar or annulus 40 is provided with an opening into which is driven a pin 70, which is employed to precompress the spring 64 during assembly.

After assembly of the pin 68 in the body member 10 and the collar 40 telescoped over the body 10, the pin 70 may be removed to allow an end of the spring to en-

gage the pin 68. The spring 64, being under compression, biases the collar 40 for rotation in a clockwise direction as viewed in FIGURES 5 and 6 to cause the cam surfaces 58 to urge or bias the balls or detents 44 radially inwardly into engagement with the circular groove or recess 50 formed in the portion 34 of guide member 28.

As shown in FIGURES 2 and 4, the body member 10 is formed with a pair of peripheral recesses, one at each side of the collar 40, the recesses being adapted to accommodate split snap rings 72 and 73 which serve to retain the collar 40 on the body member 10. FIGURE 5 illustrates the relative position of the clutch or locking collar 40 under the influence of the expansive pressure of spring 64 urging the balls 44 into locking engagement in the groove 50, this locking engagement holding the flange portion 30 against the end of the body member 10, as shown in FIGURES 1, 2, 4 and 8 to provide, in effect, a solid metal strut for the transmission of forces of impact of hammer blows on the head 17.

The assembly of guide member 28 with the body 10 as shown in FIGURES 1, 2 and 8 is for the purpose of guiding a male anchor member or stud bolt into a floor or wall 75 of concrete. The stud bolt or male anchor member 76 is adapted to be driven by the arrangement as assembled in FIGURES 1, 2 and 8. The male anchor member 76 comprises a body 77, a ledge or shoulder 78 and a threaded tenon 79, an end region of the body portion being formed with one or more slots or kerfs 80, the end of the body being roughened to promote rapid drilling by the anchor member. FIGURE 1 illustrates the initial operation of driving the body 77 of the male stud or anchor member 76 into a concrete or masonry body 75.

The threaded tenon 79 extends into the bore in the guide member 28 and the plunger portion 20 engages the end of the tenon 79. The ledge 78 engages in a recess formed in the end of the guide member 28. The operator grips the rubber handle 11 and strikes the head or anvil 17 repeated blows with a hammer or impact member 18 whereby the body 77, in effect, functions as a drill and is thus driven or sunk into the body of concrete 75, as shown in FIGURE 2. It should be noted that the driving force applied to the male anchor member 76 is transmitted through the plunger sections 14, 20, the member 28 serving as a guide means for the anchor member 76.

The plunger portion or section 16 is provided with means for indicating the depth to which it is desired to drive the stud member 76. As shown in FIGURE 2, the plunger section 16 is formed with lengthwise-spaced peripheral grooves 82 and the grooves painted with different colors providing a visual means for indicating the depth of the stud or male anchor member 76 being driven into the concrete body 75.

After the body of the stud anchor member is driven to the desired depth, the anchor stud or member is withdrawn and a wedge member, such as that shown at 84 in FIGURE 12, is inserted in the split end a short distance sufficient to frictionally retain the wedge 84 in the kerf 80, such position being shown in FIGURE 10. The drive tool is then reengaged with the threaded portion 79 in the bore in the guide member 28 and the anchor member inserted in the opening previously made by the member with the wedge 84 engaging the bottom of the bore in the concrete as shown in FIGURE 10.

The operator then strikes the head 16 with a hammer or other impact instrument to drive the stud body 79 into the bore. As the stud body is progressively driven into the bore, the wedge 84 is forced further into the kerf 80 spreading the tine portions of the stud body 79, formed by the kerf 80, laterally as shown in FIGURE 11 thus permanently anchoring the stud or anchor member in the concrete in the position shown in FIGURE 11.

The stud or anchor member 76 may be provided with crossing kerfs similar to the kerf 80, the kerfs being at

right angles one to the other, and with such construction a wedge member such as that shown at 86 in FIGURE 13 is employed, cooperating with the kerfs to spread the tines of the body portion 79 provided by the kerfs so as to fixedly anchor the stud member in its recess or opening. The drive tool of the invention is adapted for driving female anchor members of the character shown at 90 in FIGURES 14 and 17 into a concrete body.

The female anchor member 90 is inclusive of a cylindrically shaped body 92, the end region to be driven into concrete being formed with an interior frusto-conically shaped hollow region or bore 94 which forms a wall portion, the wall portion being slotted by kerfs 96 providing four tine portions 95. The anchor member 90 is provided with a threaded bore 98 of a diameter to slidably accommodate the end of the plunger portion 20 as shown in FIGURE 14, the plunger 20 serving as a guide for the anchor member 90. The opposite end of the anchor member 90 is formed with a frusto-conically shaped portion 100.

In the use of the tool for driving the female anchor member 90 into a concrete body 75, the position of the guide member 28 in the body 10, is reversed as shown in FIGURES 14 and 17. In order to reverse the assembly of the guide member 28 with respect to the body member, the operator grasps the annulus or collar 40 and rotates the same in a counterclockwise direction relative to the body 10 to the position shown in FIGURE 6, the cam surfaces 58 accommodating outward movement of the balls or detents 44 to effect a disengagement of the balls or detents with the groove 50.

The operator, while holding the spring biased collar 40 in its relative position of rotation as shown in FIGURE 6, withdraws the portion 34 of the guide member from its telescoping engagement in the body 10, reverses the guide member and inserts the portion 32 thereof into the body 10 to the position shown in FIGURES 14 and 17. The operator then releases the annulus or collar 40 and, under the influence of the expansive spring 64, the collar is rotated to the position shown in FIGURE 5, the cam surfaces 58 biasing the balls or detents 44 into wedging engagement in the groove 48 in the portion 32 of the guide member as illustrated in FIGURES 14 and 17.

The wedging action of the balls or detents 44 locks the flange or ledge 30 of the guide member 28 in contact or driving engagement with the end of the body 10 as shown in FIGURES 14 and 17.

The body portion 34 of the guide member is formed with a transverse bore 104 which is adapted to accommodate a drift pin 106 shown in FIGURE 19, the purpose of which will be hereinafter explained. The end region of the portion 34 is preferably formed with a hollow tapered interior 108 as shown in FIGURES 14 and 17.

Formed in the periphery of the anchor member 90 adjacent the base of the frusto-conically shaped portion 100 is a peripheral recess 101 to provide a weakened region adjacent the portion 100. The end region of the anchor member 90 to be driven into a concrete body is serrated or roughened as at 103 providing a plurality of teeth or projections to facilitate driving the anchor member 90 into the concrete body in forming the recess or bore to accommodate the member 90.

The operation of the arrangement employed for driving or sinking the anchor member 90 of the female type into the concrete body 75 is as follows: The guide member 28 is inserted in the end of the body 10 by the operator by manipulation of the collar 40 whereby the balls or detents 44 engage in the groove 48 to secure the portion 32 in telescoped relation within the body 10. The frusto-conically shaped portion 100 of the anchor member 90 is engaged in the hollow frusto-conically shaped end region of portion 38 of the guide member 28 and the plunger portion 20 projected into the threaded bore 98 as shown in FIGURE 14.

In this position of the plunger 20, the head portion 16 on the plunger portion 14 is in direct contact or engagement with the end of the body member 10 thus establishing a solid metal-to-metal drive strut from the head 16 through the guide member 28 to the anchor member 90. The operator then strikes the head 16 repeated blows with a hammer or other tool and drives the anchor member 90 into the concrete body 75 to form the bore 105. The anchor member is sunk into the body 75 until the recess 101 is flush with the surface of the concrete body as shown in FIGURE 17.

The anchor member 90 and the tool are then moved in a right-hand direction as viewed in FIGURE 17 to withdraw the anchor member 90 from the bore 105. The wedge member or element 110, shown in FIGURE 16, is partially entered into the hollow slotted end of the anchor member whereby the fins 112 are partially entered into the slots 96. The body of member 110, as shown in FIGURE 16, is of frusto-conical configuration to mate with the tapered hollow region 94 of the anchor member.

The anchor member 90 is then reinserted into the recess 105 and the guide member 28 reengaged with the portion 100 of the anchor member, the wedge member 110 partially entering the region 94 of the anchor member. The end or base surface 114 of the wedge member 110 engages the bottom of the recess 105. The operator then strikes the head 16 repeated blows with a hammer or other instrument to drive the anchor member 90 into the bore 105 to the position shown in FIGURES 17 and 18. In this position the wedge member 110 has moved the tine portions 95 outwardly as shown in FIGURE 19 to retain the anchor member 90 in the recess 105.

When the anchor member has been completely projected into the recess with the peripheral groove 101 substantially flush with the surface of the concrete body 75, the operator tilts the tool to a position as shown in FIGURE 18 which tilting effects a fracture of the portion 100 of the anchor member at the weakened region provided by the circular recess 101. Through this method, the female anchor member 90 is fixedly and permanently anchored in the concrete body without any portion projecting above the surface of the concrete body.

In order to remove the portion 100 of the anchor member from engagement with the guide member 28, a drift pin 106 is driven through the bore or passage 104 in the manner shown in FIGURE 19 whereby the tapered drift pin dislodges the portion 100 from the guide 28, the portion 100 being then disposed of as waste.

It will be apparent that the drive tool of the invention is readily and quickly rendered adaptable for driving or sinking both male and female anchor members simply by reversing the position of the guide member 28 with respect to the sleeve or body 10. In the use of the tool for driving or sinking female anchor members, the locking means hereinbefore described for locking the guide member 28 to the body 10 assures metal-to-metal engagement of these components to establish a solid drive thrust or transfer of forces applied to the anvil or head 17 direct to the anchor member 90.

It is apparent that, within the scope of the invention, modifications and different arrangements may be made other than as herein disclosed, and the present disclosure is illustrative merely, the invention comprehending all variations thereof.

We claim:

1. A drive tool for driving anchor elements into masonry construction comprising, in combination, a holder having a sleeve portion, a plunger slidably disposed in said sleeve portion, a guide member shaped to receive and engage elements to be driven by the tool, said guide member having a shoulder portion and a cylindrical portion projecting from each side of the shoulder portion, said cylindrical portions being adapted to be selectively entered into the sleeve portion whereby said guide member may

be reversibly mounted in said holder with the shoulder portion engaging an end of the sleeve portion, and rotatably releasable locking means for removably retaining the guide member in assembled relation with the shoulder portion engaging an end of the sleeve portion in either of its positions with the holder.

2. A drive tool for driving anchor elements into masonry construction comprising, in combination, a holder having a sleeve portion, a plunger slidably disposed in said sleeve portion, a guide member configurated with an opening adapted to receive and engage elements to be driven by the tool, said guide member having a shoulder portion and a cylindrical portion projecting from each side of the shoulder portion, said cylindrical portions being adapted to be selectively entered into the sleeve portion with the shoulder portion engaging an end of the sleeve portion and whereby said guide member may be reversibly mounted in said holder, and resiliently biased locking means for removably retaining the guide member in assembled relation with said holder in either of its positions with the shoulder portion engaging an end of the sleeve portion.

3. A drive tool for driving male and female anchor elements into masonry construction comprising, in combination, a holder having a sleeve portion, a plunger slidably disposed in said sleeve portion, a guide member being formed with an axial bore to receive elements to be driven by the tool, said guide member having a shoulder portion and a cylindrical portion projecting from each side of the shoulder portion, said cylindrical portions of the guide member being adapted to be selectively entered into the sleeve portion whereby said guide member may be reversibly mounted in said holder with the shoulder portion in contact with the sleeve portion, and resiliently biased rotatable locking means for removably retaining the guide member in assembled relation with the shoulder portion engaging an end of the sleeve portion in either of its positions with said holder, said plunger having an extension arranged to project into the bore in said guide member.

4. A drive tool for driving anchor elements into masonry construction comprising, in combination, a holder having a nonmetallic grip portion, a metal sleeve within the grip portion, a plunger reciprocably disposed in said sleeve, a guide member having passage means arranged to receive and engage elements to be driven by the tool, said guide member having a flange and a cylindrical portion projecting from each side of the flange, said cylindrical portions being adapted to be telescoped into the sleeve whereby said guide member may be reversibly mounted in said holder with the flange in engagement with an end of the sleeve, and resiliently biased locking means for removably retaining the guide member in assembled relation with the flange in engagement with an end of the sleeve in either of its positions with said holder.

5. A drive tool for driving anchor elements into masonry construction comprising, in combination, a holder having a sleeve portion, a plunger slidably disposed in said sleeve portion, a guide member shaped to receive and engage elements to be driven by the tool, said guide member having a flange and a cylindrical portion projecting from each side of the flange, said cylindrical portions being adapted to be selectively entered into the sleeve portion whereby said guide member may be reversibly mounted in said holder, means for removably retaining the guide member in either of its assembled positions with the flange in engagement with the sleeve portion of the holder, said retaining means including an annular element arranged for rotatable movement relative to said holder, detent means associated with said sleeve portion, said guide member being formed with recess means in each cylindrical portion at each side of the flange arranged to be engaged by said detent means in either position of assembly of the guide member with the holder, and means influencing the annular element toward a position biasing the detent into

guide member retaining position with the flange in engagement with the sleeve portion of the holder.

6. A drive tool for driving anchor elements into masonry construction comprising, in combination, a holder having a sleeve portion, a plunger slidably disposed in said sleeve portion, a guide member formed with a bore arranged to receive and engage elements to be driven by the tool, said guide member having a shoulder portion and a cylindrical tenon projecting from each side of the shoulder portion, said cylindrical tenons being adapted to be entered into the sleeve portion selectively whereby said guide member may be reversibly mounted in said holder with the shoulder portion engaging the sleeve portion in either selected position, means for removably retaining the guide member in either of its assembled positions with the holder, said retaining means including an annular element arranged for rotatable movement relative to said holder, detent means disposed in an opening in said sleeve portion, said guide member being formed with a recess at each side of the shoulder portion arranged to be engaged by said detent in either position of assembly of the guide member with the holder, and resilient means influencing the annular element toward a position biasing the detent into guide member retaining position with the shoulder portion in engagement with the sleeve portion.

7. A drive tool for driving anchor elements into masonry construction comprising, in combination, a holder having a sleeve portion, a plunger slidably disposed in said sleeve portion, a guide member formed with a bore arranged to receive and engage elements to be driven by the tool, said guide member having a shoulder portion and a cylindrical portion projecting from each side of the shoulder portion, said cylindrical portions being adapted to be entered into the sleeve portion selectively whereby said guide member may be reversibly mounted in said holder with the shoulder portion engaging the sleeve portion in either selected position, means for removably retaining the guide member in either of its assembled positions with the holder, said retaining means including an annular element arranged for rotatable movement relative to said holder, a ball detent disposed in an opening in said sleeve portion, said guide member being formed with a peripheral recess at each side of the shoulder portion arranged to be engaged by said ball detent in either position of assembly of the guide member with the holder, and a spring arranged to bias the annular element toward a position urging the ball detent into a peripheral recess of the guide member to hold the shoulder portion in engagement with the sleeve portion.

8. A drive tool for driving anchor members into a masonry construction comprising, in combination, a body provided with a tubular portion, a guide member shaped to receive the anchor members and having a flange portion and cylindrical portions projecting from each side of the flange portion, each of said cylindrical portions being adapted to be selectively telescoped into the tubular portion of the body with the flange portion engaging the tubular portion whereby said guide member is reversible for use in driving male and female anchor members, a plunger in said tubular portion for driving an anchor member, a locking detent carried by said tubular portion of the body, detent control means mounted on said body, and resilient means normally biasing said locking detent to a position to retain the guide member in assembled relation with the flange portion in engagement with the tubular portion of the body.

9. A drive tool for driving male and female anchor members into masonry construction comprising, in combination, a body provided with a tubular portion, a guide member formed with a passage to receive the anchor members and having a flange portion and cylindrical portions projecting from each side of the flange portion, each of said cylindrical portions being adapted to be selectively telescoped into the tubular portion of the body to engage the flange portion with an end of the tubular portion of

the body and whereby said guide member is reversible for use in driving male and female anchor members, a circumferential recess in each of said cylindrical portions, a plunger in said tubular portion for driving an anchor member, a locking detent associated with the tubular portion of the body, an annulus mounted on the tubular portion and arranged for rotatable movement relative to the tubular portion, said annulus having a cam surface arranged to influence the position of said locking detent, and resilient means engaging said annulus to normally bias said detent to a position in engagement in the recess of the cylindrical portion of the guide member extending into the tubular portion of the body to bias the flange portion into engagement with an end of the tubular portion of the body and to removably retain the guide member in assembled relation with the body.

10. A drive tool for driving male and female anchor members into masonry construction comprising, in combination, a body provided with a tubular portion, a guide member formed with a passage to receive the anchor members and having a flange portion and cylindrical portions projecting from each side of the flange portion, each of said cylindrical portions being adapted to be selectively telescoped into the tubular portion of the body with the flange portion contacting an end of the tubular portion of the body and whereby said guide member is reversible for use in driving male and female anchor members, a circumferential recess in each of said cylindrical portions, a plunger construction in the tubular portion of the body, said tubular portion of the body being formed with an opening in the wall thereof, a ball detent in said opening, an annulus mounted on the tubular portion and arranged for rotatable movement relative to the tubular portion, said annulus having a cam surface arranged to influence the position of said ball detent, and resilient means engaging said annulus for normally biasing said ball detent to a position in engagement in the recess of the cylindrical portion of the guide member extending into the tubular portion of the body to bias the flange portion of the guide member into contact with an end of the tubular portion of the body and removably retain the guide member in assembled relation with the body.

11. A drive tool for driving male and female anchor members in concrete comprising, in combination, a sleeve, a plunger slidably disposed in the sleeve and having an anvil portion at one end, a reversible guide member having a flange and a cylindrical portion extending from each side of the flange and arranged to be selectively telescoped into the sleeve with the flange in contact with the sleeve, said guide member being formed with a passage to receive an anchor member, peripheral recesses formed in said cylindrical portions, the sleeve having a wall provided with openings, locking balls in said openings arranged for cooperation with said recesses for biasing the flange into contact with the sleeve and removably retaining the guide member in either of its positions of assembly with the sleeve, an annular rotatable element mounted on said sleeve formed with cam surfaces engageable with the locking balls for influencing the position thereof, a spring, and abutment means on said element and said sleeve engaged by said spring for normally biasing the element in a direction of rotation to urge the locking balls inwardly of the sleeve for engagement in the adjacent recess in the guide member.

12. A drive tool for driving male and female anchor members in concrete comprising, in combination, a sleeve,

a plunger slidably disposed in the sleeve and having an anvil portion at one end and a portion of reduced diameter within the sleeve, a reversible guide member having a flange and a cylindrical portion extending from each side of the flange and arranged to be selectively telescoped into the sleeve with the flange in contact with the sleeve, a bore in said guide member arranged to receive an anchor member and adapted to accommodate the portion of reduced diameter of the plunger, a peripheral recess formed in each of said cylindrical portions, the sleeve having a wall provided with openings, locking balls in said openings arranged for cooperation with said recesses for biasing the flange into contact with the sleeve and removably retaining the guide member in either of its positions of assembly with the sleeve, an annular element rotatably mounted on said sleeve formed with cam surfaces engageable with the locking balls for influencing the position thereof, a spring, and abutment means on said element and said sleeve engaged by said spring for normally biasing the element in a direction of rotation to urge the locking balls inwardly of the sleeve for engagement in the adjacent recesses in the guide member, said plunger being formed with indicating means for determining the driving depth of an anchor member.

13. A drive tool for driving male and female anchor members in concrete comprising, in combination, a sleeve, a grip means of nonmetallic material surrounding the sleeve, a plunger slidably disposed in the sleeve and having an anvil portion at one end and a portion of reduced diameter within the sleeve, a reversible guide member having a flange and a cylindrical portion extending from each side of the flange and arranged to be selectively telescoped into the sleeve with the flange in contact with the sleeve, a bore in said guide member arranged to receive an anchor member and adapted to accommodate the portion of reduced diameter of the plunger, peripheral recesses formed in said cylindrical portions, the sleeve having a wall provided with openings, locking balls in said openings arranged for cooperation with said recesses for biasing the flange into contact with the sleeve and removably retaining the guide member in either of its positions of assembly with the sleeve, an annular element rotatably mounted on said sleeve formed with cam surfaces engageable with the locking balls for influencing the position thereof, a circumferential recess formed interiorly in the annular element, a spring disposed in the recess in said element, and abutment means on said element and said sleeve engaged by said spring for normally biasing the element in a direction of rotation to urge the locking balls inwardly of the sleeve for engagement in the adjacent recess in the guide member.
